UNITED STATES PATENT OFFICE.

GEORGE H. SCHÄTZEL, OF ST. LOUIS, MISSOURI, ASSIGNOR TO PFENNINGER PRETZEL & BAKING COMPANY, OF ST. LOUIS, MISSOURI, A CORPORATION OF MISSOURI.

PRETZEL-MAKING MACHINE.

1,089,725.

Specification of Letters Patent.

Patented Mar. 10, 1914.

Application filed June 19, 1912. Serial No. 704,530.

To all whom it may concern:

Be it known that I, GEORGE H. SCHÄTZEL, a citizen of the United States of America, residing at the city of St. Louis, State 5 of Missouri, have invented a certain new and useful Pretzel-Making Machine, of which the following is such a full, clear, and exact description as will enable any one skilled in the art to which it appertains to 10 make and use the same, reference being had to the accompanying drawings, forming part of this specification.

My invention relates to a pretzel making machine, and more particularly to that form 15 of machine shown and described in my prior application for patent, filed June 6, 1910, Serial Number 565,310.

In the accompanying drawings, which illustrate so much of the pretzel making machine as is necessary to disclose my invention, Figure 1 is a vertical central section through the main portion of the machine; Fig. 2 and Fig. 3 are detail views of the loop positioning brush; Fig. 4 is a front view 25 of the loop positioning brush; Fig. 5 is an enlarged sectional view showing the loop positioning brush in operation.

Like marks of reference refer to similar parts in the several views of the drawings. 30 10 represents the frame of the machine. The frame 10 carries a rotary member 11 on the periphery of which is mounted a number of loop carrying frames 12. Each 35 of these loop carrying frames 12 is provided with pins 13 which are adapted to engage with a loop of dough 14 carried on a finger 15, as shown in Fig. 1 and described in detail in my prior application above referred to. It often occurs that, in lifting the loop 40 of dough from the finger 15, the loop hangs at the extreme end of the pins 13 instead of lying close to the body of the loop-holder 12.

One of the objects of my invention is to 45 accomplish the positioning of the loop 14 upon the inner part of the pins 13 against the body of the loop-holder 12. In order to accomplish this, I provide a cross bar 16, shown in Fig. 1, to which is attached a strip 50 of sheet metal 17, having pivoted to it a brush 18. The brush 18 has a rearwardly projecting portion 19 which strikes against

the strip of metal 17 and forms a stop for holding the brush in the proper angle in the path of the holder 12 so as to engage the upper of the pins 13, as best shown in Fig. 5. 55 As the holder 12 is carried around by the rotary member 11, the pin 13 will be forced into the end of the brush as indicated by the dotted lines in Fig. 5 so as to position the loop 14 on the inner part of the pins against 60 the holder 12. After the brush has been carried upwardly, past the radial line passing through the center of the rotary member, the brush will drop back to its normal position, at the same time, passing between 65 the ends of the loop 14 as is best illustrated in Fig. 4, thus spreading the ends of the loops and insuring their proper positioning for being engaged by fingers 20 which 70 clamp the ends of the loops to the face of the clamping device 21, as has been described in detail in my previous application, before referred to.

Having fully described my invention, what I claim as new and desire to secure by 75 Letters Patent of the United States is:

1. In a pretzel making machine, the combination with a movable member, of a holder carried by said member, said holder being provided with means for receiving 80 a loop of dough, and means for forcing the loop into position on said holder.

2. In a pretzel making machine, the combination with a movable member, of a holder carried by said member, said holder 85 being provided with means adapted to receive a loop of dough, and a pivoted brush for forcing the loop into position on said holder.

3. In a pretzel making machine, the combination with a rotary member, of a holder carried by said member, said holder being provided with pins adapted to receive a loop of dough, and a pivoted brush arranged in the path of said pins whereby said pins enter the end of the brush to force said loop 95 into position on the holder.

4. In a pretzel making machine, the combination with a rotary member, of a holder carried by said member, said holder being 100 provided with means for engaging a loop of dough, and a pivoted brush arranged in

the path of said holder to swing up and down between the members of the loop, said brush being adapted to be swung from a downwardly inclined to an upwardly inclined position by contact with the holder whereby the return movement of said brush spreads the ends of the loop of dough.

In testimony whereof, I have hereunto set my hand and affixed my seal in the presence of the two subscribing witnesses.

GEORGE H. SCHÄTZEL. [L.S.]
Witnesses:

W. A. ALEXANDER,
G. M. SHORE.
